UNITED STATES PATENT OFFICE

133,503

DESIGN FOR A CABINET FOR OPTICAL SUPPLIES

Lawrence Stene, Sterling, Ill.

Application December 13, 1941, Serial No. 104,623

Term of patent 7 years

To all whom it may concern:

Be it known that I, Lawrence Stene, a citizen of the United States, residing at Sterling, in the county of Whiteside and State of Illinois, have invented a new, original, and ornamental Design for a Cabinet for Optical Supplies, of which the following is a specification, reference being had to the accompanying drawing, forming a part thereof, in which;

Figure 1 is a front perspective view of a cabinet for optical supplies, showing my new design;

Figure 2 is an end view thereof;

Figure 3 is a view similar to Figure 1, with the cabinet in an open position.

I claim:

The ornamental design for a cabinet for optical supplies, as shown.

LAWRENCE STENE.
